LOOM SHUTTLE

Gabriel Charles Beatrice, Shrewsbury, Mass., assignor to Draper Corporation, Hopedale, Mass., a corporation of Maine

Application April 25, 1935, Serial No. 18,205

4 Claims. (Cl. 139—221)

The present invention pertains to automatically threading loom shuttles and has more particular reference to such shuttles adapted to thread automatically with either right or left hand wind filling. 5 Shuttles of the type mentioned, as heretofore devised, have commonly been of the so-called "center-threading" construction wherein a threading block is provided with an outer thread guard and with inner thread guarding members 10 having between them a threading slot which is disposed centrally with respect to the longitudinal thread passage in the threading block. The filling thread occasionally escapes from beneath the outer thread guard during the second pick after 15 a transfer, at which time a centrally disposed threading slot permits the filling to escape from the inner thread guarding members and thus become completely unthreaded.

The present invention has for its object the 20 modification of inner thread guarding members and the threading slot therebetween in a manner both to facilitate the threading operation with right or left hand wind filling and also to prevent unthreading when the filling escapes from such outer thread guard as may be provided.

To this end, I have provided an automatically 25 threading shuttle wherein inner thread guarding members are constituted by fingers having a threading slot between them which preferably extends at an acute angle to the longitudinal axis of the shuttle. In the preferred embodiment, the outer end of the threading slot opens in a direction laterally of the longitudinal thread passage, for a purpose hereinafter more fully explained, 30 and the top surface of each of the thread guarding fingers is curved outwardly and downwardly so as to facilitate the threading operation with either right or left hand wind filling.

The said preferred embodiment of the invention 35 is illustrated on the accompanying drawing, of which:

Fig. 1 is a plan view of the end of a shuttle containing the threading block, the filling being of right hand wind;

Fig. 2 is a view similar to Fig. 1 but showing left hand wind filling;

Fig. 3 is a view showing the threading block in a cross-section approximately on line 3—3 of Fig. 1; and

Fig. 4 is a cross-sectional view taken approximately on line 4—4 of Fig. 3.

The shuttle shown on the drawing includes a body 1, generally of conventional construction, having a cavity 2 for the reception of a filling carrier, as bobbin 3. The shuttle is of the type

that threads automatically within two picks after the transfer to the cavity 2 of a fresh filling carrier. At the time of such transfer, the shuttle is boxed with its threading end 4 (hereinafter called the "outer" end) pointing outwardly or away from the shed (not shown) and the filling end 5 extends from the bobbin longitudinally outwardly and upwardly immediately above the shuttle. During the first pick after transfer the filling swirls about in unwinding from the bobbin and assumes its partially threaded position in the threading block. Then, during the first part of the subsequent pick the filling should assume its fully threaded position so as to emerge from the side delivery eye 5, all as is well known in the art.

The threading block of the present invention is provided with front wall 6 and rear wall 7 defining a longitudinal thread passage 8, the threading block being seated in a recess in the shuttle body so that the axis of the thread passage at least approximately coincides with the longitudinal axis of the shuttle and bobbin. The threading block is provided with a thread guard over the outer end of the thread passage, the 20 thread guard shown being comprised of a front horn 9 and an overlapping guard 10.

The outer thread guard just described is well known in the art and is widely used. It may be stated that the function of the guard is to prevent the filling end 5 from lifting out of the thread passage at the end of the first pick after transfer or beginning of the second pick. Partly because the outer thread guard does not always fulfill its intended function, and partly because 30 of the desirability of means for assisting in the threading of the filling beneath the outer thread guard, supplemental threading and thread guarding means are positioned inwardly of the shuttle from the outer thread guard.

My invention provides inner thread guarding members comprised of a pair of fingers 11 and 12 which extend, respectively, from the front and rear walls 6 and 7 of the threading block at the inner end of the thread passage 8 and overlie such passage. The fingers are constructed so that the threading block threads equally well with either right hand wind filling, Fig. 1, or left hand wind filling, Fig. 2, while still positively guarding against complete unthreading when, as in Fig. 2, the filling escapes from beneath the outer thread guard. Insofar as I am aware, this result has not been heretofore accomplished.

The fingers 11 and 12 extend from the opposite walls into proximity to each other and thence

extend generally outwardly longitudinally of the thread passage, the fingers as shown extending approximately horizontally. The contiguous relationship of the fingers provides between them a 5 relatively narrow threading slot 13 which extends at an acute angle to the longitudinal axis of the shuttle. The slot is open at both its ends. The inner end 14 of the slot opens longitudinally of the shuttle, i. e. toward the cavity 2 and may be 10 flared as shown on the drawing. The outer end 15 of the slot is displaced laterally of the shuttle relative to the inner end 14 and opens in a direction laterally of the thread passage. It will be apparent that the partially threaded filling cannot 15 be lifted out of the thread passage through the inclined, laterally opening slot, because when the filling is lifted as in Fig. 2 it will necessarily pass either in front of the finger 11 or to the rear of the finger 12 and will run in such position until 20 it automatically rethreads.

Each of the fingers 11 and 12 has its top surface 25 curved outwardly and downwardly, as shown more clearly by Figs. 3 and 4. The filling end 7 is shown by Fig. 1 to be in the position it assumes at the beginning of the first pick after transfer. The movement of the filling in unwinding from the bobbin is such that it is thrown or pulled downwardly onto the curved tops of the thread guarding fingers and thence through the threading slot 30 13 into the thread passage 8. The manner of threading is substantially identical whether the filling is right or left hand wind, and this ease of threading is accomplished without detracting from the efficacy of the thread guarding feature 35 of the fingers.

In the particular embodiment shown on the drawing, the inner end 14 of the threading slot is positioned forwardly of the longitudinal axis of the shuttle and the slot extends outwardly and rearwardly to cause the outer end thereof to be 40 positioned rearwardly of the axis of the shuttle. Obviously, it is not of paramount importance which end of the slot is positioned forwardly and which end rearwardly of the axis of the shuttle. It will likewise be apparent that the invention is 45 not restricted to the exact shape of fingers and threading slot shown.

Having fully disclosed the preferred embodiment of my invention, I claim:

50 1. An automatically threading loom shuttle having a threading block adapted to thread automatically with either right or left hand wind filling, said threading block having a longitudinal thread passage, a thread guard at the outer end of said thread passage, and opposed thread guard- 55

ing fingers positioned inwardly of the shuttle from said thread guard, said fingers overlying said thread passage and being spaced to provide a threading slot between them, said fingers and slot extending approximately horizontally at an acute angle to the longitudinal axis of the shuttle. 5

2. An automatically threading loom shuttle having a threading block adapted to thread automatically with either right or left hand wind filling, said threading block having front and rear 10 walls defining a longitudinal thread passage, a thread guard overhanging the outer end of said thread passage, and a pair of thread guarding fingers inwardly of the shuttle from said thread guard and overlying said thread passage, said fingers extending respectively from opposite of said walls and generally longitudinally outwardly in contiguous relation to each other, said fingers defining between them a threading slot which 15 extends at an acute angle to the longitudinal axis 20 of the shuttle and the outer end of which slot is open in a direction laterally of said thread passage.

3. An automatically threading loom shuttle having a threading block adapted to thread automatically with either right or left hand wind filling, said threading block having front and rear 25 walls defining a longitudinal thread passage, a thread guard overhanging the outer end of said thread passage, and a pair of thread guarding fingers inwardly of the shuttle from said thread guard and overlying said thread passage, said 30 fingers extending respectively from opposite of said walls and generally longitudinally outwardly in contiguous relation to each other, said fingers 35 defining between them a threading slot the inner end of which opens in a direction inwardly of the shuttle and the outer end of which opens in a direction laterally of said thread passage.

4. An automatically threading loom shuttle 40 having a threading block adapted to thread automatically with either right or left hand wind filling, said threading block having a longitudinal thread passage, a thread guard at the outer end of said thread passage, and opposed thread guard- 45

ing fingers positioned inwardly of the shuttle from said thread guard, said fingers overlying said thread passage and being spaced to provide a threading slot between them, the top surface of each of said fingers being curved outwardly and 50 downwardly to facilitate threading and the outer end of said slot opening in a direction laterally of said thread passage to thereby guard against unthreading of the filling.
